UNITED STATES PATENT OFFICE

GEORGE R. HARGIS, OF FREDERICK, MARYLAND, ASSIGNOR TO THE FREDERICK IRON & STEEL COMPANY, OF FREDERICK, MARYLAND, A CORPORATION OF MARYLAND

GEAR PUMP

Application filed June 12, 1928. Serial No. 284,736.

My invention relates broadly to pumps and more particularly to a compact construction of gear pump for composite mixtures of air and water.

5 One of the objects of my invention is to provide a construction of gear pump which may be manufactured from a minimum number of parts for pumping composite mixtures of air and water where the pump is provided with suction and discharge chambers having a single removable head extending across both chambers for permitting quick access to parts of the pump for repair and simplifying the mechanical assembly of the 10 pump.

Another object of my invention is to provide a compact construction of gear pump having integrally cast suction and discharge chambers with a portion of the chambers cut 15 away to receive a pair of aligned gears journaled one above the other centrally of the casting for producing suction in one chamber and discharging into an adjacent chamber a compact mixture of air and water 20 pumped from the suction chamber.

Still another object of my invention is to provide a simplified construction of gear pump having integrally cast suction and discharge chambers in which there is housed 25 a pair of drive gears in which the suction and discharge chambers terminate with means connecting opposite sides of the casting for journaling the gears in a central position within the casting.

30 Other and further objects of my invention reside in the construction of the gear pump described in the following specification and set forth in the accompanying drawings in which:

35 Figure 1 is a front view of a gear pump constructed in accordance with my invention; Fig. 2 is a lateral cross-sectional view taken through the gear pump on line 2-2 of Fig. 3; and Fig. 3 is a longitudinal cross-sectional view through the gear pump on line 3-3 of Fig. 1.

40 Referring to the drawings in detail, reference character 1 designates the base of the casting which forms the housing for the 45 pump of my construction, the base being mounted upon any suitable foundation represented at 2, and secured thereon by suitable means such as bolts, nuts or lag screws indicated at 3. The casting has its body portion 4 extending vertically into cast side portions 55 5 connected by intermediate web portions which terminate in an enlarged cast portion 7 in the interior of the casing. The suction chamber is indicated at 45 and the discharge chamber at 46. The casting is provided with 60 centrally extending bores 8 and 9 adjacent its lower extremity. The bore 8 passes partially through the cast portion 7, while the bore 9 extends partially through the cast portion 4. The suction port 10 enters the 65 left hand side of bores 8 and 9, while the discharge port 11 extends from the opposite side of the bores 8 and 9. The casting 7 is rounded on opposite sides of the center thereof to provide relatively narrow passageways 70 to and from the bores 8 and 9. I provide gears 20 and 21 carried by shafts 18 and 19 which are journaled in bearings at opposite ends thereof. I have shown one journal at one side of the pump formed by a support 22 75 which carries ball races 23 and 24 which journal the ends of shafts 18 and 19. A cover 27 is provided on the end of the bearing to which a lubricating cup 29 communicates for maintaining the bearings in proper 80 condition at all times. The cover 27 is secured in position by suitable screw members 41. The opposite ends of the shafts 18 and 19 are journaled in the ball races 25 and 26 carrying bracket member 42. The end of 85 shaft 18 is connected through the couplings 31, 32 and 33 with a driven shaft to which is secured the flange member 32 by which the pump may be driven from a suitable prime mover. The bearings 25 and 26 are housed 90 within the casing 28 to which lubricant is supplied through cup 30. The shafts 18 and 19 pass through stuffing boxes 17 formed in plates 12 which are bolted to opposite sides 95 of the casting by suitable screws 14. A tight seal is insured by means of adjustable members 16 which operate against the packing formed in the stuffing boxes 17. The top of the casting terminates in a flange 34 and to this flange there is secured a connecting plate 100

35 bolted in place by attachment members 36. The top plate 35 abuts at 43 with the upper extremity 44 of partition member 6, thus providing a complete suction chamber 45 and a discharge chamber 46. The plate 35 is provided with a central screw threaded aperture 38 and 37 located substantially along the center line of each chamber. Pipe line 39 connects to screw threaded portion 38 providing a suction inlet to the pump. Pipe line 40 connects through the plate at 37 providing a discharge outlet from the pump. It will be understood that when the rotation as shown by the arrows in Fig. 2 is reversed 10 that the suction and discharge connections are also reversed.

In order to make necessary repairs on the pump the top plate 35 may be removed to 20 secure immediate access to the interior of the suction and discharge chambers. The pump gears are readily removable by withdrawing plates 12 and removing the several bearings.

I have found the pump construction of my 25 invention extremely practical and particularly adapted for the removal of the air core in the center of a cake of ice when the ice is being frozen. The pump will operate upon a composite mixture of air and water. 30 The positioning of the vertical chamber immediately above the pump gears and integral with the pump case obviates the necessity of priming except on the initial start. The elimination of joints and fittings serves 35 to decrease leakage and increase the efficiency of the pump. The necessity of the self-priming feature of the pump becomes apparent when it is considered how the pump is normally used in practice. In the 40 manufacture of ice where there are a number of independent cans of water being frozen a hose is immersed in the can and the air which is pocketed in the composite mixture of ice and water is pumped out 45 leaving an ice cake which can be frozen solid. When the operator moves from one can to the next the end of the hose may be thrown upon the floor while the pump continues to run. The pump will stop discharging a composite mixture of water and air, but due to 50 the fact that a certain amount of water is retained in the priming or suction chamber 45 when the suction hose is immersed in the adjacent can of water the pump, after a short period, will exhaust the air from the ice core in the same manner as in the previous operation without repriming.

While I have described my invention in 55 a preferred embodiment, I desire that it be understood that modifications may be made and that no limitations upon my invention are intended other than are imposed by the scope of the appended claim.

25 What I claim as new and desire to secure

by Letters Patent of the United States is as follows:

A pump comprising a vertically extending casting having a bowl shaped interior bottom portion, and an open top portion, a 70 detachable plate member having detachable suction and discharge connections therein, a wall dividing said casting into suction and discharge chambers, beneath said suction and discharge connections on said plate member, a central web portion connected to the lower end of said wall above the bowl shaped bottom portion of said casting and projecting on opposite sides thereof and curved according to the contour of the bowl shaped bottom of said casting for establishing a substantially uniform passage extending from and leading to said suction and discharge chambers, said enlarged central portion and said bowl shaped portion having bores 80 extending therethrough, and cooperating gear devices rotatably mounted in said bores and disposed centrally with respect to said chambers and adapted to perform a pumping operation between said suction and discharge 90 chambers.

In testimony whereof I affix my signature.

GEORGE R. HARGIS.
